BICYCLE HANDLEBAR

Carlton P. Pawsat, 47 Bryant Circle, and Robert T. Humlong, 46 Bryant Circle, both of Maysville, Ky. 41056

Continuation-in-part of design application Ser. No. 23,642, June 24, 1970. This application Feb. 2, 1971, Ser. No. 112,098

Term of patent 14 years

Int. Cl. D12—06

U.S. Cl. D90—11

FIG. 1 is a front elevational view of a bicycle handlebar which shows our new design.

FIG. 2 is a perspective view thereof.

FIG. 3 is a vertical sectional view taken on line 3—3 of FIG. 1.

FIG. 4 is a perspective view of a modified form thereof.

FIG. 5 is a perspective view of a third modified form thereof.

FIG. 6 is a perspective view of a fourth modified form thereof.

FIG. 7 is a perspective view of a fifth modified form thereof.

The characteristic features of our design reside in the configuration and appearance of the horizontal portion of the handlebars.

This is a continuation-in-part of our design patent application, Ser. No. D-23,642, filed June 24, 1970, and now abandoned.

We claim:

The ornamental design for a bicycle handlebar, as shown and described.
